(57) **CLAIM**

The ornamental design for a dispenser, as shown and described.

DESCRIPTION

FIG. 1 is a perspective view of the dispenser of my design. FIG. 2 is a front elevation view thereof.

FIG. 3 is a rear elevation view thereof.

FIG. 4 is a left side elevation view, the right side elevation view being a mirror image thereof.

FIG. 5 is a top plan view thereof.

FIG. 6 is a bottom plan view thereof.

FIG. 7 is a perspective view of the components of a dispenser where the outer component is being removed for clarity.

FIG. 8 is a front elevation view of FIG. 7.

FIG. 9 is a rear elevation view of FIG. 7.

FIG. 10 is a left side elevation view of the components of FIG. 7.

FIG. 11 is a right side elevation view of the components of FIG. 7.

FIG. 12 is a top plan view of FIG. 7; and,

FIG. 13 is a bottom plan view of FIG. 7.
